UNITED STATES PATENT OFFICE.

GUSTAVUS H. ZSCHECH, OF INDIANAPOLIS, INDIANA, ASSIGNOR TO ROSA MILLER, OF SAME PLACE.

BAND-SAW WHEEL.

SPECIFICATION forming part of Letters Patent No. 359,989, dated March 22, 1867.

Application filed August 12, 1866. Serial No. 210,712. (No model.)

To all whom it may concern:

Be it known that I, GUSTAVUS H. ZSCHECH, a citizen of the United States, residing at Indianapolis, in the county of Marion and State 5 of Indiana, have invented certain new and useful Improvements in Band-Saw Wheels; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to that class of devices known as "band-saw wheels," the object thereof being to provide a band-saw wheel that shall be a non-conductor of electricity, whose rim surface shall have a powerful adhesive property, and that shall be able 20 to resist any changeable tendency resulting from variations in the density and temperature of the atmosphere; and the invention consists in the construction, combination, and arrangement 25 of the various parts, substantially as will be hereinafter described and claimed.

In the annexed drawings, illustrating my invention, Figure 1 is an elevation of my improved band-saw wheel. Fig. 2 is a horizontal 30 transverse section of the wheel and its shaft. Fig. 3 is a section, on an enlarged scale, of a portion of the rim of the wheel near one of the spokes or arms. Fig. 4 is an enlarged sectional detail of one of the arms and the portion 35 of the rim to which it is secured, and Fig. 5 is an enlarged cross-section of the rim.

Like letters of reference designate like parts in all the figures.

A represents the rim of the wheel, B the 40 hub, and D D the spokes or arms. The rim A is composed of layers of paper, pasteboard, straw-board, tar-board, &c., cemented together, and further securely united by means of the wire nails a a. The rim is made T-shaped in cross-section, as shown in Fig. 5, 45 the stem of the T forming an internal rib or flange around the inner surface of the rim. This rib is notched or cut at proper intervals to receive the blocks E E, which are bored, 50 each in a line corresponding with one of the

radii of the wheel, said blocks being for the purpose of holding the outside ends of the arms D D. The radial holes in these blocks are internally screw-threaded to correspond with the screw-threaded ends of the arms. 55 While this method of connecting the arms and blocks may be preferable, others can be employed. When the blocks are placed in the notches provided for them in the rim, they are secured to the angle-iron rings C C by means 60 of rivets c c, or otherwise. The angle-iron rings are preferably made fast to the rim A by rivets b b.

The hub B is provided with sockets F F, for holding the inner ends of the arms D D. Said 65 arms are fitted snugly in the sockets and held by pins d d. These sockets are provided with air-vents e e, which allow the escape of the air and insure that the arms shall be driven firmly into their proper places. The eye of the hub 70 B is bored taperingly, and the shaft G is likewise formed with a taper, so that it may fit tightly within the eye, when it is held immovably by means of a nut, h, engaging a screw-threaded portion of the shaft next the hub, and 75 on the end having the smaller diameter. The journals f f on said shaft G are made tapering in directions the reverse of each other, and are provided with V-shaped collars g g, which prevent any lateral motion of the wheel in its 80 bearings.

It will thus be observed that by my improved band-saw wheel, wherein the rim is composed of paper layers, the effects of electricity in impairing the quality of the steel of which the 85 saw is made are obviated, paper being a non-conductor. As shown in the drawings, these paper layers are so situated that their outer edges together constitute the outer surface of the rim. While this is the preferable arrangement, others may obviously be devised. 90

Having thus described my invention, what I claim as new, and desire to secure by Letters Patent, is—

1. A band-saw wheel consisting of a rim 95 formed of layers of paper or the like, the radially-bored blocks, the angle-iron rings, the arms, and the hub, substantially as shown and described.

2. In a band-saw wheel, the combination of 100

the rim formed of layers of paper or the like and having an inner flange, the bored blocks inserted in notches in said flange, the angle-iron rings, the hubs having sockets, and the 5 arms whose ends are secured, respectively, within the rim-blocks and the hub-sockets, substantially as described.

3. The combination of the rim A, formed of layers of paper united together, the blocks E 10 E, bored to receive the arms, the angle-iron rings C, the arms D D, the hub B, having sockets F F, and vent-holes e, all arranged substantially as shown and described.
4. In a band-saw wheel, the combination of

the rim formed of layers of paper united together, the blocks E E, bored to receive the arms, the angle-iron rings C, the arms D, the taperingly-bored hub B, and the correspondingly-tapered shaft G, secured within the hub and having reversely-inclined end portions, 20 substantially as described.

In testimony whereof I affix my signature in presence of two witnesses.

GUSTAVUS H. ZSCHECH.
